ACCORDION

Emil N. Del Principe, Chicago, Ill., assignor to
Sears, Roebuck and Co., Chicago, Ill., a cor-
poration of New York

Application March 19, 1937, Serial No. 131,851

13 Claims. (Cl. 84—376)

My invention relates to the art of musical tone modulation and more particularly to the improvement of the quality of sound produced by accordions and other instruments.

5 An object of the invention resides in the provision of a sound box or tone modulator which is adapted to be mounted on an instrument and is so constructed and arranged that when so mounted it does not increase the overall 10 dimensions of the instrument.

Another object of the invention is to provide an accordion with a horn and a control therefor.

It is also an object to provide an accordion with a sound box which does not detract from 15 the appearance of the instrument while substantially improving the quality of its tone.

A further object involves the provision of a tone modulator adapted to subdue harsh vibrant sounds produced by reed instruments such as 20 accordions.

It is another object of the invention to provide a readily attachable tone modulator adapted to replace the usual ornamental valve shield of an accordion or the like, and readily removable 25 to permit inspection.

It is a further object of the invention to provide a tone modulator so constructed as to afford increased deflection for sounds of higher pitch produced by an accordion or the like.

30 A further object is to provide a tone modulator of ornamental, durable, light and inexpensive construction.

Further objects and advantages of the invention will appear as the description proceeds.

35 Referring now to the accompanying drawings—

Fig. 1 is a front elevation of a tone modulator constructed and mounted on an accordion in accordance with the invention.

40 Fig. 2 is a side elevation and transverse sectional view taken as indicated by the line 2—2 in Fig. 1.

Fig. 3 is an isometric view of the tone modulator.

45 Fig. 4 is a longitudinal sectional view taken as indicated by the line 4—4 in Fig. 3.

Fig. 5 is a back view of the modulator seen in Fig. 4.

50 Fig. 6 is an enlarged fragmentary sectional view taken as indicated by the line 6—6 in Fig. 3.

Fig. 7 is a fragmentary sectional view taken as indicated by the line 7—7 in Fig. 6.

55 Referring now more particularly to the drawings, a tone modulator or sound box embodying the invention is indicated generally at 10

mounted at the head 11 of an accordion adjacent the keyboard 12 in such manner as to shield the reed valves 13 and associated mechanism. The box has an edge which may be readily slipped into and out of nested or interfitting relation to 5 and held in place by the rim 14 of the head and by the black keys of the keyboard. To assist in the assembly, end guide brackets 15 carried by the head are arranged to be received within the ends 16 of the box, and receive readily releasable 10 means such as screws 17 extending thru said ends and securely holding the box in place.

The box comprises a hood whose ceiling or top 18 has an elongated opening 21 which is of gradually increasing width toward the lower 15 pitch reeds, when mounted on the instrument. This opening is covered by a superimposed hood 22 which is preferably of reduced width and height at the wider end of the opening and is of gradually increasing dimensions toward and 20 beyond the narrow end of the opening, terminating preferably in a bell mouth 23. The upper hood and the covered portion of the lower hood provide together a tone modulating horn whose throat is formed by the opening 21, the remainder of the lower hood serving as a resonance 25 or sound board.

To control the quantity of vibrant air entering the horn and provide additional means of escape of sound, the front wall 25 of the box has 30 a series of passages 26 backed by a slide 27 having like passages 28. The slide is guided by straps 29 and is actuated and arranged in adjusted positions by any suitable control means such as a screw knob 31 threaded to a lug 32 on 35 the slide. This means is readily accessible by the fingers of the player. By adjusting the slide, varying quantities of vibrant air from the instrument may be diverted from the horn, or all of the air may be allowed to escape thru the 40 horn, thereby rendering the box flexible in operation and affording a variety of tonal effects while at the same time effectively modulating and subduing rasping and other sounds produced by the instrument.

The box may be constructed of light, preferably 45 stiff acoustically efficient material capable of resonating without undesirable overtones thru-out the entire pitch range of the instrument.

Improved tonal quality is additionally provided by virtue of the arrangement whereby the more rasping notes, which are of the higher 50 pitches, are subjected to correspondingly greater deflection so that the rasping qualities are subdued.

It will be observed that the box is so dimensioned as to lie well within the overall dimensions of the instrument so that it does not project obtrusively therefrom. The mouth of the horn may be so arranged as to emit the waves forward or in any other desired direction.

It will be appreciated that the invention is applicable to other reed instruments such as concertinas and flutinas.

Although the various parts of the structure embodying the invention may be united by fastening means of any suitable character, they are preferably integrally united substantially as shown so that the structure may be as homogeneous as possible.

I am aware that many changes may be made and numerous details of construction may be varied thru a wide range without departing from the principles of this invention, and it is not intended that the terminology employed herein be

restrictive or confining, and I therefore do not purpose limiting the patent granted hereon otherwise than as necessitated by the prior art.

I claim:

1. An accordion comprising a valve head, a shield secured over said head and comprising a sound box having an opening of gradually decreasing width and a horn-like hood of correspondingly increasing width over said opening.

2. An accordion comprising a valve head, a shield secured over said head and comprising a sound box having an opening of gradually decreasing width from the lower to the higher pitched reeds, and a horn-like hood of correspondingly increasing width over said opening.

3. An accordion or the like comprising a valve head, and tone modulating means mounted over said head and providing increased deflection of sound waves from the lower to the higher pitched reeds, and a horn-like hood mounted over said means.

4. An instrument of the accordion type having a valve head, a sound box mounted on said head and having a horn and also having a substantially unobstructed tone passage arranged to divert vibrant air from said head away from said horn.

5. An accordion or the like comprising a valve head, a sound box mounted over said head and having a horn, and means for varying the volume of sound emitted from said horn.

6. An accordion or the like comprising a valve head, a sound box over said head and provided with a substantially unobstructed horn and with tone passages arranged in a series longitudinally of said head, a slide carried by said box and having a similar series of passages arranged to vary the effective size of the first series, and means for adjusting said slide.

7. An accordion or the like comprising a valve head, a sound box over said head and provided with substantially unobstructed tone passages arranged in a series longitudinally of said head, means for varying the effective size of said series, and a horn substantially coextensive with said series.

8. An accordion or the like comprising a valve head, a sound box over said head and having a wall substantially coextensive with said head and an elongated opening in said wall, an elongated hood over and extending well beyond said opening, said hood having an opening spaced from the first mentioned opening and said hood being of gradually increased size toward its opening, said wall extending inward from the sides of said hood and cooperating with said hood to form a horn.

9. An accordion or the like having a valve head, and a horn mounted over said head and disposed substantially within the overall length and width of said head, and means for varying the volume of sound emitted from said horn.

10. A tone modulator for an accordion or like instrument, said modulator comprising a cover adapted to be positioned over the tone producing mechanism of the instrument, a cover mounted over the first cover and almost entirely sealed thereto, leaving an opening therebetween, said first cover thereby forming a bottom wall for the second cover, said wall and second cover together being shaped to form a horn and said wall having an opening forming the throat of the horn.

11. A tone modulator for an accordion or like instrument, said modulator comprising a cover for the tone producing mechanism of the instrument, a cover over the first cover and almost completely joined thereto, leaving an opening therebetween, the first cover thereby providing a bottom wall for the second cover, said wall and second cover together being shaped to constitute a horn, said wall having an opening forming the throat of the horn, and means for controlling the sound issuing from the horn.

12. An accordion or the like having a piano keyboard and a valve head, and a tone modulator having a horn and directly interfitted with said head, leaving substantially the entire lengths of the black keys accessible to the fingers without cramping.

13. An accordion or the like comprising a valve head, a sound box mounted over said head and having a horn, adjustable means for varying the volume of sound emitted from said horn, and means for maintaining the adjustable means in any desired adjustment.

EMIL N. DEL PRINCIPE.

CERTIFICATE OF CORRECTION.

Patent No. 2,189,531.

February 6, 1940.

EMIL N. DEL PRINCIPE.

It is hereby certified that error appears in the printed specification of the above numbered patent requiring correction as follows: Page 2, first column, line 54, claim 6, for the words "with a substantially unobstructed horn and with" read with a horn and with substantially unobstructed; and that the said Letters Patent should be read with this correction therein that the same may conform to the record of the case in the Patent Office.

Signed and sealed this 16th day of April, A. D. 1940.
